FAN SUPPORT

Gustav H. Koch, Springfield, Mass., assignor to
Westinghouse Electric & Manufacturing Com-
pany, East Pittsburgh, Pa., a corporation of
Pennsylvania

Application September 14, 1938, Serial No. 229,813

11 Claims. (Cl. 230—256)

My invention relates to a supporting structure for air translating apparatus, and has for an object to provide an improved structure of this kind.

5 It is a further object of the invention to provide an improved structure for resiliently supporting a fan, which structure affords tilting of the fan and motor in a vertical plane.

10 A further object of the invention is to provide an improved resilient support of the character set forth having provisions for housing the fan control switch.

15 It is a further object of the invention to provide a structure of improved appearance for adjustably and resiliently supporting a fan and its controlling device, which structure may be economically manufactured.

20 These and other objects are effected by my invention as will be apparent from the following description and claims taken in accordance with the accompanying drawings, forming a part of this application, in which:

25 Fig. 1 is a view in perspective of a fan of the pedestal type having my invention applied thereto;

Fig. 2 is a side view of the fan shown in Fig. 1 having a portion thereof shown in section taken along the line II—II of Fig. 3; and,

30 Fig. 3 is a section taken along the line III—III of Fig. 2.

Reference will now be had to the drawings wherein I have shown my invention applied to an oscillating fan of the pedestal or floor mounting type and including a motor 10, air translating fan blades 11 driven thereby and a supporting column 12 having a base 13. The motor 10 has a shaft 10a upon which the fan blades 11 are mounted. The motor 10 is tiltably supported in accordance with my invention by a resilient supporting structure, generally indicated by the numeral 14 and carried by the column 12.

35 The support 14 includes a swivel member 15 having a chamber 16 and a hollow boss 17 formed therein. A pair of opposed trunnions 18 are 40 formed on the exterior of the member 15 and are seated in spaced rings 19 formed of resilient material such as, for example, rubber. Support for the rings 19 is provided by spaced saddles 21 preferably formed in the upper end of the column 12. Each of the rings 19 is positioned in its saddle 21 by a pair of arcuate clamps 22, which are 45 pivotally secured to the column 12 by pins 23. The free ends of the clamps 22 are joined by a screw 24 having a nut 25 threaded thereon.

50 When drawn tightly, the screw 24 moves the

5 clamps 22 toward each other whereby the ring 19 is compressed for gripping its associated trunnion 18 and thereby frictionally positioning the support 14 and motor 10. Tilting of the motor 10 upwardly and downwardly in a vertical plane about the axis of the trunnions 18 is effected by loosening the screws 24 for reducing the compression of the rings 19 and, therefore, the friction between the rings 19 and the trunnions 18. Accordingly, the motor and support 14 10 may be tilted to the desired position, after which the screws 24 are tightened. The direction of the air stream is adjusted vertically by the adjustment just described. It is desirable that the amount of adjustment vertically be limited and 15 this feature is effected by the pins 23 which define stops as they are engaged by bottom portions of the member 15 in the extreme positions thereof.

20 The motor 10 is pivotally carried by the member 15 so that it may be oscillated. A substantially vertical pintle 26 is secured as by welding, to the frame of the motor and is carried by a thrust bearing 27, and a journal bearing 28 disposed within the hollow boss 17. The thrust 25 bearing 27 is preferably of the anti-friction type, as shown, and is carried by the member 15 adjacent the top thereof. Movement of the pintle 26 upwardly is prevented by a screw 29, the end of which is disposed within a groove 31 formed in 30 the pintle 26.

Control of the fan motor 10 is effected by a switch 32 that is disposed in the chamber 16 as best shown in Fig. 2. The switch 32 may be secured to a cover 33 that closes the chamber 16 35 and includes an operating chain 34 disposed exteriorly of the chamber 16. The line side of the switch 32 is connected to a conductor 35 that is preferably disposed in the column 12 and led exteriorly thereof in any well understood manner. 40 The load side of the switch is connected to the motor 10 by a flexible conductor 36 that extends through an insulating bushing 37 in the cover 33.

Oscillation of the fan motor 10 about the axis 45 of the pintle 26 may be effected by any suitable mechanism. As shown, the oscillating mechanism includes a relatively slow speed shaft 38 that carries an internal gear 39 having a crank pin 41 secured therein. A rod 42 connects the crank pin 41, in accordance with my invention, with a stationary pin 43 carried by an extension 44 of the supporting member 15. (See Figs. 1 and 3.) The slow speed shaft 38 is journaled in a housing 45 secured to the motor 10 in any suitable manner and housed within a casing 46. 55

Rotation of the gear 39 and shaft 38 is effected by a pinion 47 having a shaft 48 journaled in the housing 45. A gear 49 meshing with a worm wheel 52 driven by the motor shaft 10a, effects 5 rotation of the shaft 48. A clutch mechanism generally indicated at 51 controls rotation of the shaft 48 so that the fan may be operated either as an oscillating fan or as a non-oscillator, as desired. As the clutching mechanism 51 forms 10 no part of the present invention, it has not been shown or described in detail.

It will be understood that any suitable oscillating mechanism may be employed and that the one shown is disclosed by way of example. The 15 specific oscillating mechanism which I have shown is disclosed more fully and claimed in my copending application Serial No. 234,519 filed October 12, 1928, and assigned to Westinghouse Electric & Manufacturing Company. As the 20 crank pin 41 is rotated about the axis of the shaft, oscillation of the fan motor 10 about the axis of the pintle 26 is effected by the connection of the rod 42 with the stationary pin 43, as is well understood.

25 My improved supporting structure 14 defines a tiltable resilient support for the fan motor 10 having provisions for housing the control switch 32, which structure may be economically manufactured and readily assembled. In this connection, it will be noted that by forming the saddles 21 in the column 12 so that they provide a seat for the flexible rings, machining of a separate casting for this function is eliminated. The construction including the resilient rings 19 and their 30 clamps 22 provides a swivel for the fan motor. Forming the swivel member 15 hollow to receive the switch obviates the necessity of otherwise providing a mounting for the switch. Furthermore, the pins 23 for the clamps 21 are so disposed that they provide stops for the member 15. 35 This organization of elements effects a more pleasing appearance as will be apparent from Fig. 1, when compared with structure of this type heretofore provided.

40 In operation, vibrations originating in the supported rotating structure are insulated by the resilient rings 19 and are not transmitted to the column 12 or its base, whereby more quiet operation is afforded. It will be apparent from the foregoing that I have provided an improved 45 swivelling support for air translating apparatus having provisions for absorbing vibrations. The support may be economically manufactured and presents a pleasing appearance. While I have shown a relatively large air circulator for floor 50 mounting, it is to be understood that my invention is not so limited and may be applied 55 equally well to smaller fans such as, for example, of the desk and bracket type.

60 While I have shown my invention in but one form, it will be obvious to those skilled in the art that it is not so limited but is susceptible of various changes and modifications without departing from the spirit thereof, and I desire, therefore, that only such limitations shall be 65 placed thereupon as are imposed by the prior art or as are specifically set forth in the appended claims.

What I claim is:

70 1. In air translating apparatus, the combination of a motor, fan blades driven thereby, a pedestal, a swivel member tiltably supported by the pedestal, said member enclosing a chamber, a switch for controlling operation of the motor and enclosed within said chamber, and means 75 pivotally connecting said motor to said member

with the motor disposed exteriorly of said member.

2. In a resilient support for a fan motor, the combination of a substantially vertical column having spaced saddles formed in the top thereof, spaced resilient rings carried by the respective saddles, and a member for supporting the fan motor and having opposed trunnions extending laterally into the resilient rings, said member being adapted to support the fan motor with the 10 axis thereof extending transversely of the axis of said resilient rings and said trunnions and being adjustable about the latter axis for tilting the fan motor. 15

3. In a resilient support for a ventilator including an electric motor and fan blades driven thereby, the combination of a substantially vertical column having spaced saddles formed in the top thereof, spaced resilient rings supported by the respective saddles, a member for supporting the fan motor and including opposed trunnions extending laterally into the resilient rings, said fan motor being pivoted to said member on an axis transverse of the axis of said trunnions, said member having a chamber formed therein, and a switch for controlling operation of the motor disposed within said chamber. 20

4. In air translating apparatus, the combination of a motor, a fan driven thereby, a member for pivotally supporting the motor, means connected to said member for oscillating the motor, opposed trunnions for supporting said member, spaced resilient rings encompassing the trunnions and defining a support therefor, said member and trunnions being tiltable within the rings, 30 and means for compressing the rings so that the member and its trunnions are maintained in a substantially fixed position. 35

5. In a fan, the combination with a motor and fan blades driven thereby, of a member for carrying the motor and pivotally connected thereto, spaced trunnions fixed to the member on an axis transverse to the axis of the pivotal connection, a substantially vertical column having spaced 40 saddles formed thereon, resilient rings carried by the respective saddles and encompassing said trunnions, whereby said member and the motor are tiltable relative the column, and means for compressing the resilient rings for frictionally engaging the trunnions so that the motor and said member are maintained substantially in the 45 position to which they are tilted. 50

6. The combination as claimed in claim 5 in which said member defines a chamber, and a switch disposed in the chamber for controlling 55 the operation of the motor.

7. In air translating apparatus, the combination of a motor, fan blades driven thereby, a member for pivotally supporting the motor, means for resiliently supporting said member and means for oscillating the motor, said oscillating means being operatively connected to the resiliently supported member. 60

8. In a resilient support for a fan including an electric motor and fan blades driven thereby, the combination of a substantially vertical column, a member resiliently supported by said column adjacent the upper end thereof, a pivot for the motor carried by said member, and means for oscillating the motor about said pivot, said 70 oscillating means being operatively connected to a portion of said member. 75

9. In air translating apparatus, the combination of a motor, fan blades driven thereby, a member having a chamber formed therein and 75

provided with means for pivotally supporting the motor, means for resiliently supporting said member, means for oscillating the motor about its pivot, said oscillating means being operatively connected to the resiliently supported member, and a switch for controlling the operation of the motor and disposed within said chamber.

10. In air translating apparatus, the combination of a motor, fan blades driven thereby, a substantially vertical column having horizontally spaced saddles formed adjacent the upper end thereof, spaced resilient rings disposed within the respective saddles, a member having opposed trunnions disposed within the resilient rings, a substantially vertical stem for supporting the motor and pivotally carried by said member, and means for oscillating the motor and stem, said

oscillating means including an arm pivoted to said member.

11. In air translating apparatus, the combination of an electric motor, fan blades driven thereby, a swivel member having a pair of spaced trunnions and formed with a chamber disposed at least partly between said trunnions, a supporting member having means for frictionally and releasably engaging said trunnions, whereby the swivel member may be tilted to different positions relative to the supporting member, means for mounting the fan motor on the swivel member to pivot about an axis transverse to the axis of said trunnions, and a switch for controlling the operation of the motor and enclosed within said chamber. 5 10 15

GUSTAV H. KOCH.
